UNITED STATES PATENT OFFICE.

CHARLES W. BEHRENS, OF LANCASTER, OHIO.

CHICKEN-BROODER.

1,179,269.

Specification of Letters Patent. Patented Apr. 11, 1916.

Application filed September 8, 1913. Serial No. 788,700.

To all whom it may concern:

Be it known that I, CHARLES W. BEHRENS, a citizen of the United States, residing at Lancaster, in the county of Fairfield and 5 State of Ohio, have invented certain new and useful Improvements in Chicken-Brooders; and I do declare the following to be a full, clear, and exact description of the invention, such as will enable others skilled in the art 10 to which it appertains to make and use the same, reference being had to the accompanying drawings, and to the letters and figures of reference marked thereon, which form a part of this specification.

15 This invention relates to improvements in chicken-coops generally, more especially that type termed "brooders" for chicks.

The invention has for its object to facilitate and promote the care or raising especially of chicks, particularly in the following particulars: By quarantining or isolating the roosts at night, more especially for the protection of the chicks against the ravages of rats and the like. By suitably 20 accommodating or dividing up or separating the chicks with the view of preventing overcrowding. By providing for the ready and easy removal and replacing or handling of the chicks. By providing for the ready and 25 effective cleaning of the coop and its maintenance in a thoroughly sanitary condition. By making provision for the thorough or effective ventilation of the coop. By rendering the chicks immune from vermin, such as 30 infest chicken-coops. By providing a "knock-down" coop for portability and facility in shipping and storing the same.

A still further object of the invention is to carry out the aforesaid ends in a simple, 40 economical and expeditious manner.

The invention consists of certain instrumentalities and features of construction substantially as hereinafter fully disclosed and defined by the appended claims.

45 In the accompanying drawing is illustrated the preferred embodiment of my invention wherein it will be understood that various changes and modifications may be made as relate to the detailed construction 50 and arrangement of the parts without departing from the spirit of the invention, and in which drawing:

Figure 1 is a side elevation of my improved brooder chicken-coop. Fig. 2 is a 55 plan view thereof with the closure or top removed. Fig. 3 is a sectional elevation of

the coop with a supplemental wire netting chamber opposed adjacent thereto. Fig. 4 is a detached perspective view, especially of the brooder chamber for the chicks, the removable or auxiliary bottom thereof being displaced to an adjacent position.

In carrying out my invention I provide or construct a coop 1 suitably gotten up of separable or "knock-down" sections 2, 65 preferably constituted of spaced-apart slats or members, each section having its base or lower portion preferably reinforced with transverse boards or imperforate members 3 along one side and its ends, the remaining 70 side at that point having only a horizontal or transverse strip 4 secured thereto so as to leave a space or opening there-below 5 through which the coop may be cleaned as presently seen. Staples and hooks 6 and 7, 75 respectively, are applied to the imperforate members or boards 3 and strips 4, the hooks being right-angled to reach around the corners and engage the staples. The sections 2 aforesaid have attached to their upper ends 80 transverse or horizontal strips 8, which strips are, however, not connected to each other, the same also reinforcing those points.

A suitable closure or top 9, preferably in the form of a roof, is suitably supplied to 85 the body-portion of the coop, the resultant of the above described sections, said roof or closure having base-strips 10 at its respective sides and ends resting upon the upper edges of the strips 8 of said body forming 90 sections, the lateral or side-strips 10 having secured thereto an additional strip 11 terminating in handle-forming extensions 12 for the convenient lifting off and on of the closure or roof 9. The roof or closure 9 has 95 a preferably upwardly extending ventilator-chute 13 about centrally in its ridge or apex portion, said ventilator chute having horizontally hung or pivoted valves 14 for controlling the air circulation in the brooder 100 when elevated, as will be more apparent later. The roof or top 9 has a suitably closed opening 15 therein through which convenient access may be had to the chicks for their removal and replacement as occasion may require, the closure for said opening being designated as 16 and suitably hinged to the roof or top 9.

A brooding chamber 17 of general tray-like construction having preferably upwardly flared or inclined sides and ends is supplied to the chamber of the body-portion 110

of the coop for receiving the chicks. Said chamber has an auxiliary or supplementary bottom 18 of suitable material, wood, cardboard or the like, which bottom is readily 5 removable through one side of said chamber to provide for the convenient disposition of the deposits thereon from the chicks, as in cleaning the coop or brooding chamber, said chamber having that side or lateral 10 wall thereof formed of a member 19 hinged or pivoted at its upper edge to the ends of said chamber to swing vertically for that purpose as it may be suitably actuated by the application of the hand thereto. The 15 brooding chamber 17 may be suitably partitioned off into compartments of the required capacity according to the quantity of chicks it may be found requiring accommodation therein to prevent the over-crowding 20 of such compartment or compartments. Or possibly it may be more properly stated that where it may be found that in event of the tendency of the crowding, or rather over-crowding, of any one of the compartments 25 the partitions 20 of pieces of suitable material, as board or the like, arranged in the brooding chamber, may be readily adjusted therein by slipping the upper edge endwise extensions or projections 21 of said partitions along the upper edges of the lateral walls of said chamber and be suitably held against displacement by suitably provided turn-buttons 21^a. The end and lateral walls 30 of the brooding chamber and the partitions 35 20 may all be, or rather are, suitably lined or padded as at 22 and 24, respectively, for attracting the vermin, such as infest fowl, from the chicks thereto as is well understood, thus rendering the chicks immune 40 thereto and accordingly promoting the care thereof.

The brooding chamber 17 is adapted to be suitably adjusted into an elevated position to protect the chicks from the ravages of 45 rats or other rodents, especially at nights, preferably by means of a sling-like contrivance 25 including looped flexible connections of twine or wire 26 with their ends secured to the end-walls of the brooding chamber, 50 said flexible connections being secured together about centrally and having the centrally secured-together portion caught or suspended preferably by a hook or eye 27 at the lower end of a second flexible connection 55 of twine or wire 28 passing over a pulley 29 suitably hung in the ridge or apex

portion of the roof or cover 9, the free end of the flexible connection or member 28 being adapted to be suitably controlled by the operator for elevating the brooding chamber 60 at the required time and for lowering the latter as required.

It will be noted that the spaced apart slats of the sections 2 provide air passages 1^a therebetween and the members 8, which passages admit air from the outside into the upper part of the coop, the air thus admitted being delivered downwardly into the brooder, especially when in elevated position, to displace the impure or foul air 70 therein and thus promote sanitary conditions and accordingly the condition of the chicks, the amount of air admitted being controlled by the ventilating valves 14.

A reticulated or woven-wire receptacle 30 75 may be provided and disposed adjacent to the chicken-coop and adapted to be brought into communication therewith as a recreative chamber or annex of the coop, as will be readily appreciated. 80

I claim:

1. A device of the type described, including an inclosure having a brooding chamber provided with compartment forming partitions having lateral or end extensions 85 adapted to rest upon the upper edges of the lateral walls of said brooding chamber, and turn-buttons applied to the inclosure and engaging said extensions.

2. A device of the type described, including a chicken-coop having an apex-roof whose apex has an air-circulating passage about centrally therethrough, a brooding chamber, and suspending means for said brooding chamber comprising a sling-like 95 flexible connection formed of looped members with their ends secured to the end-walls of said brooding chamber, and a further flexible member having hooked connection about centrally with the aforesaid flexible 100 connection and extending over a rotary bearing hung about centrally of the apex of said chicken-coop roof, said chicken-coop having air-circulating passages arranged laterally of said brooding chamber. 105

In testimony whereof, I affix my signature, in presence of two witnesses.

CHARLES W. BEHRENS.
